DOOR KNOB

Ernest L. Schlage, Burlingame, Calif., assignor to
Schlage Lock Company, a corporation

Filed May 2, 1962, Ser. No. 69,933

Term of patent 14 years

(Cl. D50—3)

FIG-1

FIG-2

FIG-3

FIG-4

FIG-5

FIGURE 1 is a perspective view of a door knob showing my new design;

FIGURE 2 is a side elevation of the door knob shown in FIGURE 1;

FIGURE 3 is a front elevation of the door knob shown in FIGURE 1;

FIGURE 4 is a rear elevation of the door knob shown in FIGURE 1; and

FIGURE 5 is a cross section, the plane of which is indicated by the line 5—5 of FIGURE 4.

I claim:

The ornamental design for a door knob, as shown.
